Edgar Goff, Attorney

UNITED STATES PATENT OFFICE.

FRANK H. HOWARD, OF READING, PENNSYLVANIA, ASSIGNOR TO READING CHAIN AND BLOCK CORPORATION, OF READING, PENNSYLVANIA, A CORPORATION OF PENNSYLVANIA.

ROPE GUIDE.

Application filed February 14, 1925. Serial No. 9,101.

To all whom it may concern:

Be it known that I, FRANK H. HOWARD, a citizen of the United States, residing at Reading, in the county of Berks and State of Pennsylvania, have invented certain new and useful Improvements in Rope Guides, of which the following is a specification.

This invention relates to improvements in rope guides and it is intended more particularly for use in connection with the rope or cable used in hoists, or other instances where a cable or rope is wound on a rotating drum.

The invention consists of a frame having a slot in which moves a cross-head, which cross-head is provided with rollers or rotatable bearing members, between which the cable or rope passes, and which acts as a guide for the rope at all times, being slideable on the frame.

20 The invention is more fully described in the accompanying specification and clearly illustrated in the drawing forming a part of this application.

Figure 1 is a side elevational view of a winding drum with my invention applied to the hoisting cable. Figure 2 is a plan view of the cross-head and frame, showing the cable in section. Figure 3 is a sectional view taken vertically through the cross head and frame, showing the rollers.

25 The numeral 1 designates a winding drum and 2 a cable adapted to encircle it. The numeral 3 designates a frame formed with a slot 4 through which the winding cable 30 passes.

The numeral 5 designates a cross-head, mounted on the slotted frame, and adapted to slide freely thereon. This cross-head is provided with a set of rollers comprising 40 four members 6, two of which are located on the upper portion and two on the lower

portion, and the members of each pair are separated sufficiently to permit the cable to pass vertically between them.

This cross-head is so located that cable 45 passes through the centre thereof and also through the slot in the frame, and as the cable is wound upon the drum, the cross-head will be moved along on the slotted frame and always keep the cable in vertical 50 alinement and prevent its doubling or folding over upon itself as it is wound. This alinement is kept at all times, even though the tension upon the end of the cable is at an angle, as indicated in Figure 1, because 55 the cross-head, when the "pull" is other than vertical, will bite into the surface of the slotted frame, and will not move freely, as it does when the pull is vertical.

This tendency of the cross-head to keep 60 the cable between it and the winding drum in perfect alinement, will insure the proper winding of the cable at all times, because, no matter at what angle the rope bears, as it approaches the cross-head, it will be held 65 in proper winding position by the cross-head.

What I claim is:—

In a rope guide for hoists, a frame having 70 an elongated slot therein, a cross-head slidably mounted upon said frame, two pairs of rollers carried by the cross-head between which the rope passes, and a winding drum upon which the rope is wound, said cross-head being capable of longitudinal movement on the frame through the action of the cable passing through it and being tilttable thereon, whereby a binding action is effected between the cross-head and the frame when the rope leads off at an oblique angle. 75

In testimony whereof I affix my signature.

FRANK H. HOWARD.
